UNITED STATES PATENT OFFICE.

HEINRICH ANTON FRANZ BERNHARD HERMANN TÖNNIES, OF GRONINGEN,
NETHERLANDS.

ACETYLENE-GAS GENERATOR.

SPECIFICATION forming part of Letters Patent No. 734,634, dated July 28, 1903.

Application filed May 22, 1901. Serial No. 61,419. (No model.)

To all whom it may concern:

Be it known that I, HEINRICH ANTON FRANZ BERNHARD HERMANN TÖNNIES, a subject of the Queen of the Netherlands, and a resident of Groningen, in the Kingdom of Netherlands, have invented certain new and useful Improvements in Acetylene-Gas Generators, of which the following is a specification.

For the purpose of utilizing acetylene gas in small illuminating bodies for the purpose of street traffic—such as, for instance, cycle and carriage lamps—the following conditions in the construction must be observed. The generator and burner apparatus should occupy little space and be combined into a small body. The generator must, notwithstanding its smallness, be capable of supplying the gas to the burner for a considerable time at a uniform rate and in a pure condition. The generator should be rendered safe against danger of explosion by tight and simple closing means so arranged as to render the interior of the generator readily accessible. All these conditions are completely embodied in the acetylene-generator constructed in accordance with my invention, and in order that the nature of my invention may be understood I will describe the same by way of example as applied to a cycle-lamp, although it is to be well understood that I do not limit the application of my said invention thereto.

In the accompanying drawing I have shown a sectional elevation of my improved acetylene-generator in combination with a cycle-lamp.

According to this invention the generator is formed with four main chambers communicating with each other—viz., the water-chamber *a*, the carbid-chamber *b*, the gas-collecting or gasometer chamber *c* for the generated acetylene gas, and a separate gas-passage chamber *d* between the carbid-chamber *b* and the collecting-chamber *c*. The gas-passage chamber *d* possesses peculiar features. It forms an annular jacket around the water-chamber *a*, which is advantageously funnel-shaped, and opens at its lower end into the cover of the carbid-chamber *b* and communicates at its upper end with the gas-col-

lecting chamber *c* through a small opening *e*, provided at the farthest or remotest end from the burner *f*. The narrow, although extensive, passage of the gas-passage chamber *d* entirely prevents water and impurities being carried into the collecting-chamber *c* and to the burner *f*, so that there is no possibility of the fine burner-holes becoming choked and the flame extinguished. The gas-passage chamber *d* therefore insures the proper supply of acetylene gas in a pure condition to the burner.

In order that the supply of gas to the burner may be uniformly carried on, I arrange the collecting-chamber *c* between the burner *f* and the carbid or generating chamber *b*, and I further provide special means for closing the water-supply to the carbid during too excessive generation of gas. To this end the water-chamber *a*, which is preferably funnel-shaped, is formed with a double bottom, of which the apex of the funnel forms the lower bottom, a second or false bottom *h* being provided above same, so as to form a small space or chamber *g*. The bottom and the apex have an outlet hole or orifice *h'* and *g'*, respectively, and in the upper hole *h'* is fitted a needle-valve *i*, adapted to be so adjusted as to either close the aperture *h'* entirely or to allow more or less water to drip through. Each water-drop falls on the lower bottom—*i. e.*, into the apex—and only escapes through the opening *g'* of this latter when the gas-pressure in the carbid-chamber *b* allows it to do so. After the gas-pressure reaches a certain height the water-drop is retained above the lower opening *g'* by the pressure of the gas, and thus also away from contact with the carbid. In this manner the water-supply is temporarily interrupted until the gas-pressure has been sufficiently reduced. This mode of automatic regulation of the water-supply cannot be effected with a single bottom opening arranged immediately beneath the water, for the reason that the direct pressure of the water column above causes the water to drip, the gas-pressure being insufficient to prevent it, whereas with my improved arrangement the pressure of the gas generated is capable of retaining separate water-drops which have fallen on the second bottom surface

and are freed from the pressure of the water column above.

By the arrangement hereinbefore described the gas is generated for a long time in a uniform manner and is supplied to the burner in a pure condition, while at the same time the construction is such as to provide for a safe and yet readily detachable connection between the collecting-chamber *c* and the carbid-chamber *b*.

The bottom *c'* of the gas-collecting chamber *c*, which at the same time forms the cover of the carbid-chamber *b*, is formed with a screw-threaded flange *k* and a groove *k'* for the reception of an elastic packing-ring *l*. To the flange *k* is secured the internally-screw-threaded rim *m* of the box forming the carbid-chamber *b*. The rim *k* is provided with a lip or channel *m'*, adapted to carry a second packing-ring *n* to form a tight joint with the flange *k'* of the cover, while the first-described packing-ring *l* forms a tight joint with the inner rim *m'* after the box forming the carbid-chamber has been screwed onto the flange *k* of the collecting-chamber *c*. This method of forming the joint for the carbid-chamber effectually prevents the escape of gas directly to the exterior, while at the same time both the carbid-chamber and the gas-passage chamber are readily accessible for recharging with carbid or for cleaning.

What I claim to be new, and desire to secure by Letters Patent, is—

1. An acetylene-lamp comprising a generator, a conical reservoir above the same having its outlet in the apex, and means for controlling the flow of water from said reservoir to the generator; in combination with a gas-chamber and an annular gas-passage surrounding the reservoir and communicating 35 with said gas-chamber, substantially as and for the purpose specified.

2. An acetylene-lamp comprising a gas-chamber having a downwardly-flaring bottom and an axial conical opening, and a generator secured to the gas-chamber below its bottom; in combination with a conical reservoir of less diameter than the opening in the gas-chamber and arranged axially within said opening to form an annular gas-passage, 45 the apex of said reservoir projecting axially into the generator, a port *e* in the inner wall of the gas-chamber near its upper end and a gas-delivery pipe carrying a burner *f* in the outer wall at or near the lower end of said 50 gas-chamber, substantially as and for the purpose set forth.
